UNITED STATES PATENT OFFICE.

LEROY B. TAYLOR, OF CLEVELAND, OHIO.

REVERSIBLE METAL WINDOW.

Application filed April 10, 1923. Serial No. 631,200.

To all whom it may concern:

Be it known that I, LEROY B. TAYLOR, a citizen of the United States, residing at Cleveland, in the county of Cuyahoga and State of Ohio, have invented certain new and useful Improvements in Reversible Metal Windows, of which the following is a specification.

This invention relates to metal windows and casings thereof, and has for its object to provide a window in which the sashes swing on horizontal pivots so that they can be reversed for cleaning purposes or opened to any extent desired, and in which the parts are so constructed and arranged that the window will stay in the position in which it is set.

The invention may be embodied in various forms, some of which are illustrated in the accompanying drawings in which Fig. 1 is a partial front elevation of one form. Fig. 2 is a vertical section with the sash closed. Fig. 3 is a similar view with the sash open. Figs. 4 and 5 are horizontal sections, enlarged, on the lines 4—4 and 5—5 of Fig. 2. Fig. 6 is a partial front elevation of another form. Fig. 7 is a vertical section of Fig. 6. Fig. 8 is a similar view to Fig. 7 with the sashes in open position. Fig. 9 is a detail in section of another modification. Figs. 10 and 11 are details in perspective of parts shown in Fig. 9.

In the form shown in Figs. 1 to 3 the upper sash swings inwardly and the lower sash swings outwardly, and referring particularly thereto, 6 indicates the masonry in which the casing is set. This casing includes side frames 7 which are stepped and flanged to form guides, and these side pieces extend the full length of the window. The side pieces are connected at the top by a cross frame 8 and at the bottom by a sill plate 9, the inner edge of which is flanged upwardly as at 10 and then outwardly as at 11 for a purpose to be described.

Inasmuch as the lower sash swings outwardly and the upper sash swings inwardly, the sides of the former must be spaced from the casing a sufficient distance to enable the

sash to clear the adjacent masonry at the sides, and for this reason the lower half of the window has at each side a face plate 72 which covers a space sufficient to permit the outward swing of the lower sash, as will be evident from Fig. 5.

The upper sash is indicated at A and the lower sash at B, the sash frame consisting of two angle plates 12 and 13 in the upper sash and 12^a and 13^a in the lower sash, between the flanges of which the glass 14 is set. Referring to the upper sash, it has a weather strip piece 15 attached to the outer side of the frame 12 and projecting in position to enter a recess 16 between one of the faces of the casing 7 and a flange 17 on a bead or facing piece 18 which extends up beside the window and is set in or otherwise fixed to the masonry. This piece 18 also has a recess 19 in which the projecting edge 20 of the frame 12 fits to assist in sealing the joint, a double seal being thus formed by the pieces 15 and 20 fitting within the spaces or grooves in the casing members.

A roller 21 is mounted on a pin 22 projecting from each piece 15, and this roller travels in a guide in the casing formed by the frame 7 and an angle piece 23 secured thereto. The lower edge of sash A thus moves up and down with the roller 21 as the sash is opened or closed. A link 24 is pivoted at 25 to the casing, at one end and is pivoted at 26 at the other end to a tubular lever member 27 in which slides a bar 28. The member 27 is offset at one end as indicated at 29 and pivoted at 30 to the side frame 12 of the sash A. The bar 28 has a head 31 connected by a fixed pivot 32 to the casing 7 near the top of the latter, and the bar 28 slides with some friction in the member 27, forming a telescoping lever connected at one end to the casing and at the other end to the sash, and also connected by the link 24 to the fixed pivot 25 on the casing.

By means of this construction the sash A may be swung to open or closed position. When swung to closed position, the roller 21 travels in its guide downwardly and the

tube 27 slides upwardly on the bar 28, whereby the sash closes to vertical position with the lever and link substantially parallel and the flanges 15 and 20 enter the recesses to 5 make a weather-tight joint, as indicated in Fig. 4. To open the sash, the top is pulled out. The effect of this is to draw the tube 27 outwardly on the bar 28, and each roller 21 rides in its guide upwardly so that the 10 sash can be set at any angle desired or completely reversed so that the outside of the glass is accessible for cleaning purposes.

The lower sash B swings outwardly by similar arrangement, except that the lever is 15 pivoted at 32° near the bottom of the casing, and at the other end the telescopic tube 28° is pivoted to the sash, and to make the joint the sash frame 18° is extended inwardly as at 13° to fit in a recess 13° formed in 20 a piece 40 which is set in the casing behind the face plate 12 and is properly stepped and provided with an angle bar 41 to form a guide for a roller 21° which travels up and down in a manner similar to that above 25 described, and the sash is spaced inwardly a sufficient distance to swing outwardly and clear the adjacent masonry.

The lower bar 47 of the sash B is flanged upwardly as indicated at 42 to engage under 30 the lip 11 of the sill 9, and also has a downwardly projecting flange 43 which stops against the sill thereby making a tight joint when the sash is closed. The lower bar of the upper sash also has a lip 44 which covers 35 the joint between the sashes when they are closed as shown in Fig. 2.

In the modified form shown in Figs. 6 and 7, both sashes open inwardly, hence the construction is the same as that above described 40 with respect to the sash A, the lower sash B' being equipped with the same arrangement of telescoping levers and links as that disclosed with respect to the sash A, the spacing plates 12 and other parts associated with 45 the sash B being omitted. However, in this form, the lower bar 50 of the upper sash has a groove on its under side which receives a rib 51 on the upper bar of the lower sash B' when the sashes are closed, and the lower bar 50 of the sash B' is grooved to receive a rib 53 on the sill plate 9°. These ribs do not interfere with the swinging movement of the sash, because when the upper sash is opened, its first movement is to lift slightly, just 55 after it begins to swing inwardly, withdrawing the bar 50 from engagement with the rib 51 and permitting the complete swing of the sash, and then the lower sash B' may be swung, and lifted to clear the lower bar 52 from the rib 53. Thereupon both sashes may 60 be swung to open position as shown in Fig. 8, or completely reversed if desired.

Figs. 9, 10, and 11 illustrate a modification with respect to the means for assembling the 65 members of the casing. In this form, each

side piece 7 of the casing is slotted to make off-set tongues 7° at its inner edge, and these tongues are set in a dove-tail groove 18° in the bead member 18, thereby locking the casing and the external bead. The bead may 70 be slid onto the casing endwise or it may be assembled by expanding the flange at the side of the recess 18° and then pressing the same inwardly to grip the casing to complete 75 the dove-tail joint.

By the means described, a metal window and casing can be constructed so that it can be easily swung to open or closed position, and the friction, especially between the telescoping lever members, will be sufficient to 80 hold the sash in any position, which action is assisted by the manner of pivoting the parts.

I claim:

1. The combination with a window casing and sash, the sash having a pin at the side which travels in a vertical guide in the side of the casing, of a telescoping lever pivoted at one end to the casing and at the other end to the sash, and a pivoted link connection between the lever and the casing. 85

2. The combination with a window casing and sash, the sash having a pin at the side which travels in a vertical guide in the side of the casing, of a telescoping lever pivoted at one end to the casing and at the other end to the sash, and a pivoted link connection between the lever and the casing, the link being arranged to swing to substantial 90 parallelism with the lever when the sash is 100 closed.

3. The combination with a window casing and sash, the sash having a pin at the side which travels in a vertical guide in the side of the casing, of a telescoping lever pivoted at one end to the casing and at the other end to the sash, and a pivoted link connection between the lever and the casing, the link being pivoted to the casing at a distance 105 from the point at which the lever is pivoted 110 to the casing.

4. The combination with a window casing and sash, the sash having a pin at the side which travels in a vertical guide in the side of the casing, of a telescoping lever pivoted at one end to the casing and at the other end to the sash, and a pivoted link connection between the lever and the casing, the telescoping lever comprising inner and outer 115 members slideable with respect to each other, 120 and the link being pivoted to the outer member.

5. The combination with a casing, of upper and lower horizontal swinging sashes therein, and a lever and link connection between the side of each sash and the casing, the sides of the one sash being spaced inwardly 125 from the casing a sufficient distance to clear the outside of the casing, so that it may be 130 swung outwardly, and a pair of face plates 130

beside the outwardly swinging sash and covering the space between the sides of the sash and the sides of the casing.

6. The combination with a casing, the side members of which have vertical guides, of a sash having rollers at the sides thereof which travel in said guides, an extensible lever pivoted at one end to the casing and at the other end to a sash at each side of the latter, and a

link pivoted at one end to the lever and at the other end to the casing at each side of the latter.

In testimony whereof, I affix my signature in presence of two witnesses.

LERoy B. TAYLOR.
